CLAIM

The ornamental design for the bait bucket, as shown and described.

DESCRIPTION

FIG. 1 is a front elevational view of the bait bucket showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is cross-sectional view thereof shown in a use position, the broken line showing of the pail for illustrative purposes only and forming no part of the claimed design.
